F. E. LIBBEY

PROCESS OF MAKING WOODEN SPOONS

Filed June 6, 1927

Inventor:
F. E. Libby
by: C. J. Fetherstonhaugh
Attorney.

UNITED STATES PATENT OFFICE.

FRANK ELVERT LIBBEY, OF LENNOXVILLE, QUEBEC, CANADA.

PROCESS OF MAKING WOODEN SPOONS.

Application filed June 6, 1927. Serial No. 196,823.

The invention relates to a process of making wooden spoons and the objects of the invention are to eliminate as far as at present seems possible hand work in the construction of wooden spoons having flat, curved handles; to produce a symmetrical and well finished spoon; to reduce the costs of manufacture in such articles through the use of special methods and machines capable of being carried out and operated by unskilled labor; and generally to provide in turning out spoons increased production at an equal expenditure of time and labor and maintain the efficiency, and it consists essentially of the mass production hereinafter set forth in its several stages with reference to the accompanying drawings, and pointed out in the claims for novelty following:—

In the drawings, Figure 1 is a side view showing an outline of a machine used in the forming of the blanks from the wedge shaped blocks.

Figure 2 is an outline of the same machine from one end view.

Figure 3 is an outline of the machine for shaping the bowl end and handle of the spoon.

Figure 4 is a perspective view showing the wedge shaped block used in making these spoons.

Figure 5 is a perspective view of a blank following the first reduction of the wedge shaped block.

Figure 6 is a perspective view showing the blank scooped out at one end in forming the bowl.

Figure 7 is a perspective view showing the blank cut away to outline the bowl and handle.

Figure 8 is a perspective view of the spoon showing the final shaping of the bowl.

Figure 9 is a perspective view of the finished spoon.

Like numerals of reference indicate corresponding parts in the various figures.

These line drawings are merely added to facilitate the understanding of the description of the process as carried out.

In the manufacture of this spoon, the blocks 10 are of wedge shape, though the

process may start with the shaping of these blocks, however, they are preferably ordered in that way, and are fed in quantities one after the other on to a carriage indicated 55 by the numeral 11 in the machine, the ends of the block being propelled by the lugs 12 in said carriage and securely held at the ends.

The blocks successively are pushed 60 through the cutters 13 and 14, which leave an uncut portion 15 at one end and an uncut portion 16 at the other end for gripping purposes. The end portions 16 may be cut off before leaving the first machine or after 65 as desired. The bowl 18 of the spoon is made in the thicker end 17 and extends through the gripping portion 15 and in the cutting step of the process this thicker end is formed with a dip at the beginning of the 70 bowl, which levels this spoon in relation to its handle.

These blanks formed by the first cutters are delivered by the machine as explained, and the bowl 18 formed. The gripping portion 15 at the bowl end is trimmed and the reduced block with the bowl recess is fed downwardly through cutters, which give a contour to the bottom and edges of the bowl and at the same time shape the handle 75 80 19.

In the shaping of the spoon after the first cuttings the blocks are fed into a machine having cutters performing the trimming act and removed in succession preferably being fed in at the top of the machine and taken away under the cutters.

The bottom of the bowl is then carefully shaped in a wood working machine of conventional design, so as to give it a nicely 90 rounded surface, extending from a comparatively thick neck 20.

The spoon is fixedly smoothed in an abrading or grinding device and sandpapered to thoroughly clear it from all roughnesses.

The main steps in the process are accomplished by automatic machine operating on a particularly shaped block and in the production of wooden spoons this does not seem to have been known before.

The salient features in this invention are first the use of the wedge-shaped block, then

the continuous operation of the cutters on succeeding blocks in the formation of the spoon blanks, then the trimming of the blanks in rapid succession, and then the finishing work.

What I claim is:—

The herein described process of making wooden spoons consisting of first shaping a wooden block in the form of a wedge and 10 clamping the ends thereof in a cutting ma-

chine, then cutting the upper and lower sides away between the clamped ends, then scooping out the bowl of the spoon, still leaving the ends unfinished and finally shaping the bowl and handle on the under and upper 15 sides and coincidentally cutting away the unfinished ends used for clamping purposes.

Signed at Sherbrooke, Quebec, Canada, this 13th day of May, 1927.

FRANK ELVERT LIBBEY.
